UNITED STATES PATENT OFFICE.

IRVIN E. BARRICLOW, OF DALLAS, TEXAS.

PROTECTING ALARM-CIRCUIT.

SPECIFICATION forming part of Letters Patent No. 591,725, dated October 12, 1897.

Application filed June 22, 1896. Serial No. 596,506. (No model.)

To all whom it may concern:

Be it known that I, IRVIN E. BARRICLOW, a citizen of the United States, and a resident of Dallas, in the county of Dallas and State of Texas, have invented certain new and useful Improvements in Protecting Electric Alarm-Circuits, of which the following is a specification.

The object of my invention is to protect a place or an object by means of an electric circuit so applied and combined with an alarm and other apparatus that the protected place or object cannot be broken into or the protecting-circuit broken or short-circuited without giving an alarm at the alarm-station.

In putting my invention into effect I employ an alarm device or other suitable indicator held normally inoperative by two balanced powers, either of which actuates the alarm or indicator in the event of the other losing power or in the event of gaining power itself. One of these balanced powers is an electromagnet, while the other may be a spring or any equivalent device, and an arm or other moving part arranged to actuate the alarm by movement in either of two directions is brought under control of these two balanced powers and by them normally held in an intermediate position. The electromagnet constituting one of these powers is included in the line-circuit to be protected, and means is employed for maintaining a constant current on this line-circuit. In order to prevent tampering with the line-circuit, this current-controlling resistance is duplicated, one resistance being located at the local station and the other at the distant point to be protected, and pole-changers are employed adjacent to the respective resistances in order to introduce them alternately in the line-circuit, so that while the effect on the electromagnet is the same as if one resistance remained in all the time it is obvious that should the line be tampered with the distant resistance, which is of known length and equal to the local resistance, will fail to do its duty and the equilibrium which holds the alarm inactive will be destroyed.

In addition to the foregoing features my invention consists in novel details in the arrangement of the parts and current-reversing apparatus, as will hereinafter be fully

described, and particularly pointed out in the claims.

In the accompanying drawings, Figure 1 is 55 a diagrammatic view illustrating the complete system. Figs. 2, 3, and 4 are detail views showing, respectively, the two pole-changers and the commutator on the local pole-changer, which reverses the current on 60 the line and actuates the distant pole-changer.

1 represents the alarm, which may be in the form of an ordinary electric bell and under control of a circuit composed of the wires 2 3 4 and including a battery 5, two contact-points 6 7, and an arm 8, pivoted at 9 and vibrating between the contacts 6 and 7. Upon the pivot 9 of the arm 8 is mounted a spring 10, which tends to swing said arm against the contact 7, and also an armature 11, which 70 is under the influence of the poles 12 of electromagnet 13 and tends to swing the arm 8 against contact 6.

14 is an arm by means of which the tension of the spring 10 may be regulated at will. 75

15, 16, and 17 represent the local wires of the line-circuit, which includes the electromagnet 13 and a local standard battery 18. These wires also connect with a pole-changer 20 at the local station and through it with 80 the main-line wires 21 and 22, which lead to the distant point to be protected.

23 23^a represent a network of conductors forming a part of the main line and forming a cover and a lining to the inclosure for parts 85 of the system which are located at the distant point, and this network of conductors is such that the inclosure cannot be tampered with without breaking the circuit, which fact will be immediately indicated at the local station. 90

24 is a pole-changer within the protected inclosure.

In order to maintain a constant current over the line 15, 16, 17, 21, and 22 and through 95 magnet 13, a local resistance 25 is employed, which, together with the standard battery 18, will serve this purpose. In order that it may be known at all times whether the distant protected point remains undisturbed and in circuit, a precisely similar resistance 25^a is located at said distant point, and these resistances 25 and 25^a are connected by shunt-wires 26 27 and 26^a 27^a, and the pole-changers

20 and 24 are arranged to operate synchronously and alternately introduce these resistances into the line-circuit. If, therefore, the distant resistance should not be regularly 5 interposed and withdrawn from the line at the proper time, or if an attempt should be made to introduce some other resistance not precisely the equivalent of the local resistance 25, the equilibrium between electromagnet 13 and the spring 10 would be destroyed and the alarm set in operation. The same effect would be produced if any accident should take place.

The distant pole-changer 24 is actuated by 15 the local pole-changer 20, and in order that the local pole-changer 20 may produce the necessary alternations in the circuit 21 22 and simultaneously cut in and out the local resistance 25 said pole-changer consists, preferably, of a permanent magnet 28 and an electromagnetic armature 30, carrying commutator-plates 30, 31, and 32. Contact-brushes 33 and 34 bear alternately upon the plate 29 and upon one of the plates 31 and 32. 20 Now since the wire 21 is connected with the plate 30 and the wires 22 and 26 are connected, respectively, with the plates 31 and 32 it is obvious that the current from battery 18 as supplied by wires 15 and 17, connected, respectively, with brushes 33 and 34, will be 25 alternated in direction over the distant part of the line-circuit represented by wires 21 and 22, and simultaneously with these alternations the resistance 25 will be switched in 30 and out. The distant pole-changer 24 comprises permanent magnet 35 and electromagnetic armature 36, included in the line-circuit, and by means of contact-pins 37 38, connected through the medium of armature 36 35 and outside network 23 with the wire 22, and the contact-brushes 39 and 40, connected, respectively, with resistance 25^a and the wire 21 through medium of inside network 23^a, the resistance 25^a is switched in and out in 40 continuous operation. Moreover, from the 45 position of the parts as shown it will be observed that one of the resistances is switched in while the other is cut out.

It remains only to provide actuating means 50 for the combined pole-changer and current-reverser 20. This consists of a clockwork 41 or other equivalent constantly-moving mechanism having a vibrating arm 42, which is connected by a wire 43 with one end of electromagnetic armature 29, the other end of which is connected by wire 44 with an intermediate point 45 of the battery 5, hereinbefore referred to. Contacts 46 47 are connected by wires 48 49 with the opposite poles 55 of said battery 5. If arm 42 rests in the position against contact 46, the current from battery 5 passes to armature 29, which is thereby made to assume the position in which it is shown. By said armature the resistance 25 60 is cut out and current is directed from battery 18 over the line in the direction shown by featherless arrows, and the pole-changer

24 assumes the position in which it is shown with the resistance 25^a switched in. The electromagnet 13 gains no advantage nor is overcome by spring 10 and the alarm remains inactive. When the arm 42 passes to the position shown by dotted lines, the current is reversed through armature 29 and passes in the direction of feathered arrows. The armature is 75 also reversed so as to bring contact-plate 29 beneath brush 34 and plate 32 on brush 33 when the resistance 25 is switched in. The current is reversed in the direction of feathered arrows over the distant line 21 22. Simultaneously armature 36 is shifted and resistance 25^a is cut out.

From the foregoing description it will be understood that as the arm 42 is carried upon the balance-wheel of a clock mechanism it 85 alternates the current over the circuit 43 44 continuously, and by this means the pole-changers 20 and 24 are vibrated and the resistances 25 25^a alternately introduced and withdrawn from the line-circuit synchronously and in continuous operation. Therefore the state of equilibrium of the alarm-actuating device 13 remains undisturbed; but as both resistances and pole-changers must coöperate to maintain this balance it is 95 obvious that any interference with the line would result in sounding the alarm apparatus.

Having thus described my invention, the following is what I claim as new therein and desire to secure by Letters Patent:

1. In a device for protecting electric circuits, the combination of a suitable alarm, an electromagnetic device controlling said alarm and arranged to be held normally inoperative by a current of certain intensity, a circuit 105 including both the alarm-actuating device and the distant object to be protected pole-changers located in said circuit at the station and at the distant object respectively, resistances adjacent to the respective pole-changers and adapted to be alternately introduced into the said circuit, and means for actuating the pole-changers synchronously as and for the purposes set forth.

2. In a device for protecting electric circuits, the combination of an alarm or equivalent indicator, a normally open circuit controlling same, a circuit-closer interposed in said alarm-circuit, an electromagnet combined with said circuit-closer so as to keep 120 the same normally open but permit it to close upon a change taking place in the current passing through said magnet, a line-circuit including said electromagnet and leading to the distant point to be protected, a resistance 125 arranged in shunt with said line-circuit, a pole-changer having a local circuit for actuating it and combined with the line-circuit in such manner as to reverse the current therethrough and to simultaneously cut in and out 130 the resistance arranged in shunt therewith, a pole-changer located at the distant point to be protected and actuated by alternations on the line-circuit, and a resistance at said dis-

tant point alternately cut in and out by said pole-changer; the pole-changers being synchronous in action and the two resistances being equal and introduced alternately into the line-circuit as explained.

3. In a device for protecting electric circuits, the combination of an alarm device or indicator held normally inactive by a current of constant measure and duplicate sets of apparatus located respectively at the alarm-station and at the distant point to be protected and each comprising a resistance, contacts for cutting said resistance alternately in and out and synchronously but oppositely vibrating circuit-closers moving back and forth between the two contacts, to alternately effect changes in the line-circuit in continuous operation, such changes being the same in character and together maintaining the constancy 15 of the current which controls the alarm device.

4. In a device for protecting electric circuits, the combination of an indicator held normally inactive by a constant current over the circuit to be protected, and means for de-

tecting interference with said circuit consisting of two resistances located respectively at the indicator-station and at the distant point, a pole-changer at the distant station for alternately cutting in and out the resistance there, a pole-changer at the indicator-station 25 for cutting in and out the resistance there alternately with the resistance at the distant station, and also simultaneously reversing the current over the line-circuit, a clock-work or equivalent mechanism having a constantly-vibrating part, wires connecting the respective ends of the local pole-changer with the middle point of a battery and with the constantly-vibrating part, and contacts co-operating with said vibrating part and connected respectively with the opposite poles 30 of said battery, substantially as and for the purposes set forth.
